(57) **CLAIM**

The ornamental design for a knife, as shown and described.

DESCRIPTION

FIG. 1 is a left side view of a knife according to my new design, the right side view thereof being a mirror image of the left side view;

FIG. 2 is a bottom plan view thereof;

FIG. 3 is a top plan view thereof;

FIG. 4 is an enlarged rear view thereof;

FIG. 5 is an enlarged front view thereof;

FIG. 6 is a left side perspective view thereof as viewed from the top; and,

FIG. 7 is a left side perspective view thereof as viewed from the bottom.

The broken lines in the figures form no part of the claimed design.

1 Claim, 7 Drawing Sheets

FIG. 1

FIG. 2

FIG. 3

FIG. 4

FIG. 5
